FIG. 5

FIG. 7

FIG. 1 is a left side elevational view of a fertilizer spreader trailer embodying my new design;

FIG. 2 is a right side elevational view thereof;

FIG. 3 is a right front elevational view thereof;

FIG. 4 is a rear elevational view thereof;

FIG. 5 is a right top front perspective view thereof;

FIG. 6 is a left rear top perspective view thereof; and

FIG. 7 is a top plan view thereof.

The jack, gear lever, and drive shaft are omitted from FIGS. 5, 6 and 7, and the tongue in FIG. 7 is broken away for convenience of illustration.

The dominant features of my design reside in the full line portions of the drawing.

I claim:

The ornamental design for a fertilizer spreader trailer, as shown and described.
